RALPH J. WELLS, OF DAYTON, OHIO.

RAILWAY JOINT-TIE.

1,258,837.

Specification of Letters Patent. Patented Mar. 12, 1918.

Application filed June 12, 1917. Serial No. 174,175.

To all whom it may concern:

Be it known that I, RALPH J. WELLS, citizen of the United States, residing at Dayton, in the county of Montgomery and State of Ohio, have invented certain new and useful Improvements in Railway Joint Ties, of which the following is a specification:

My invention relates to railway track structures and more particularly to a new and novel form of cross tie therefor, especially a joint tie for supporting the adjacent ends of succeeding rails.

The object of the invention is to simplify the structure of such devices whereby they will not only be cheapened in construction, but will be more efficient in use, of maximum strength, safe in operation, and unlikely to get out of repair.

20 A further object of the invention is to provide an improved form of sleeper or support for the rail ends which will afford a degree of resiliency simulating that of the earth embedded wooden tie formerly used, while possessing the permanency of modern concrete constructions.

30 A further object of the invention is to provide a tie construction which is easily capable of transportation and readily adaptable to different conditions of use and which may be readily and quickly assembled into the track construction, and in which the perishable parts including the fastenings, the sleeper blocks and cushions if such be used, may be quickly and conveniently replaced.

With the above primary and other incidental objects in view as will more fully appear in the specification, the invention consists of the features of construction, the parts and combinations thereof and the mode of operation, or their equivalents, as hereinafter described and set forth in the claims:

45 Referring to the drawings, Figure 1 is a perspective view of the cross tie forming the subject matter hereof with the railway rails supported thereon. Fig. 2 is a perspective view of the tie viewed in different position with the rails and rail-attachment members removed. Fig. 3 is a detail perspective view partly broken away, of one of the sleeper blocks and its inclosure. Fig. 4 is a detail

perspective view of one of the connecting or tie bars. Fig. 5 is a transverse sectional view of a track construction embodying the tie forming the subject matter hereof.

Like parts are indicated by similar characters of reference throughout the several views.

The invention forming the subject matter hereof is analogous to that shown and disclosed in Letters Patent of the United States, No. 1,218,141, issued March 6, 1917. It has been found in practice that a tie of special design and arrangement of the sleeper blocks is desirable for use under rail joints, under special track constructions or conditions of use such as in conjunction with signal or interlock apparatus.

Referring to the drawings, 1-1 are the rails to be supported. It is the approved practice to "break" joints or offset joints of the opposite rails in relation one with the other. By this arrangement joints in the respective rails do not ordinarily occur directly opposite one from the other. Where such rail joints occur, however, it is desirable that the rails be supported for ample distance on either side of the joints in order that there may be no tendency for the ends of the rails to be depressed or to yield in relation one with the other when subjected to heavy traffic.

To this end, the rail joint tie forming the subject matter hereof comprises a single elongated sleeper for the abutting rail ends at one side of the track and independent spaced sleepers for the continuous single rail at the opposite side of the track. These three sleeper units are interconnected by tie bars or reinforcement bars to form a single unitary structure. This tie structure is adapted to be embedded in a concrete body. Each tie structure may be embedded in a separate concrete body or the road bed may be concreted in sections and each section be made to include a series of ties.

The tie comprises an elongated box or receptacle 2 preferably of sheet metal but which may be of fiber, composition, or other suitable material adapted to retain its shape when embedded in the concrete body. This elongated receptacle is connected by transverse angle bars or tie members 3-3 with similar boxes or receptacles 4-4 spaced one

from the other and also from the elongated receptacle or box 2. The tie bars or reinforcement members 3—3 may be connected to the boxes or receptacles 2 and 4 in any 5 suitable manner such as by electric welding, riveting, bolting or by other means. As shown in the drawing, these tie bars are preferably of angle iron which are fitted to the base corners of the boxes or receptacles 2 10 and 4. They may, however, be attached by means of the rail attachment or retaining bolts hereafter mentioned. The intermediate bars or transverse reinforcement members are preferably flattened as indicated at 15 5, Fig. 4, at points coincident with the elongated box or receptacle 2 which engages within the notch or recess in the flange or the bar and rests upon the flat or outturned flange portion. 20 Fitted within the boxes or receptacles 2 and 4 are sleeper blocks 6 of wood, fiber, composition or other suitable material. These sleeper blocks are proportioned and shaped approximately to the inside dimensions of the receptacles or boxes 2 and 4 25 within which they are inserted.

Before inserting the sleeper blocks 6 within said receptacles, a cushion or bed 7 may be provided of asphaltum or other suitable 30 resilient material. In the event that asphaltum or other material capable of assuming a semi-fluid state is employed, the sleeper blocks are proportioned sufficiently accurate in relation with the interior dimensions of the receptacles or boxes 2 and 4 35 as to form a closure to prevent the escape of such cushion material when softened by summer heat and subjected to heavy traffic pressure. It has been found in practice that 40 if the sleeper blocks do not conform sufficiently close to the walls of the receptacles or boxes the cushion material when in its semi-fluid state will be forced out of the receptacles or displaced by said blocks under 45 pressure of heavy traffic. However, this cushion material will not readily pass through a restricted crevice between the blocks and the walls of the receptacles or boxes. It is not necessary that the blocks 50 should closely conform but only that the crevice intervening between the block and the wall of the box or receptacle shall be sufficiently restricted to prevent the free discharge of the cushion material. This crevice 55 is sealed by a film or coating of asphaltum 6 or other suitable material which will exclude water or moisture from the sleeper blocks.

It has been found that for some conditions 60 of use the cushion 7 beneath the sleeper block may be entirely omitted and the resiliency of the sleeper block 6 relied upon independent of said cushion. In order that the vibration of the rail ends as traffic passes 65 to and fro over them may not wear the

top surface of the sleeper block 6 but shall be unyieldingly held in relation one with the other, a bearing plate 8 of metal is interposed between the sleeper block and the rails as shown in Figs. 1 and 2. This bearing plate distributes the pressure of the rail 70 equally over the elongated sleeper block and prevents the ends of the rails wearing hollows or depressions in the upper face of the block by their independent vibration. 75

The blocks and supported rails are retained in their adjusted position by means of retaining bolts 9 extending through the bottom of the box or receptacle and through the sleeper blocks 6 positioned therein and 80 thence through the superposed bearing plate 8 and carrying at their upper ends clamping plates 10 which engage the base flanges of the rails 1. These retaining bolts 9 are so positioned in relation with the transverse connecting bars or reinforcement members 3 that they will also pass through the underlying flanges of said bars. However, as before mentioned, these bars may be connected to the boxes or receptacles by other 90 means independent of said retaining bolts.

While for ordinary conditions of use, the tie is preferably of a bifurcated formation having an elongated sleeper at one end and the short spaced sleeper members at the opposite end, however, for unusual conditions of use and particularly for special track work particularly cross-overs, switches, etc., it may be desirable to provide an elongated sleeper at each end of the tie such sleepers 95 being connected by the intermediate transverse multiple connecting bars or reinforcement members 3—3. The sleeper blocks preferably extend somewhat above the level 100 of the tops of the receptacles or retaining boxes and are free to move downward against the tension of the underlying cushion material 7 when such is employed. Their upward movement, however, is limited 105 by the clamp plates 10. 110

In placing the tie in use, parallel trenches may be excavated across the road bed in the positions to be occupied by the ties and such trenches or excavations may be used as forms for independent concrete ties in 115 which the tie structure before described will be embedded or the road bed may be excavated throughout. In the latter case, the excavation is preferably deepened by longitudinal trenches at each side beneath the 120 positions occupied by the receptacles or boxes 2 and 4.

The excavations of the desired size and proportions having been provided the tie structure heretofore described is then attached to the base flanges of the rails by means of the clamping plates 10 in proper relation one with the other. The track rails are then blocked up or adjusted to proper grade and are leveled as is usual in track 125 130

construction. The skeleton ties are thus held suspended beneath the track rails and within the excavated cross trenches or within the excavated road bed. The excavations 5 of the road bed are then filled with grouting or concrete as indicated in Fig. 5. This grouting extends around and beneath the boxes or receptacles 2 and 4 and the connecting angle bars or reinforcement members 10 3. The upper face of the grouting or concrete may if desired extend over the edge of the receptacle into close proximity to the sleeper block positioned therein. This 15 serves to further cover or close the current space between the sleeper block and the interior wall of the receptacle or box.

It is obvious, however, that the skeleton structure heretofore described may be embodied in independent ties manufactured at 20 a distance from the point of use.

While the receptacle and inclosed sleeper block have been shown in the drawings as located close to the ends of the tie structure it will be understood that they may be located at any desired point or points throughout 25 the length of the connecting angle bars or reinforcement members 3. This will be found especially convenient in the placing of special track work such as crossings, 30 switches, etc.

In track constructions for electrical railways the skeleton construction heretofore described forms a cross bond or electrical connection between the respective rails.

35 It is found in practice that the construction as above described affords a structure of great durability possessing the required degree of resiliency, and which is convenient and economical to install. While the 40 use of an underlying cushion of resilient material is desirable particularly in conjunction with sleeper blocks of comparatively rigid material, it will be found that for certain conditions of use, or when sleeper 45 blocks of more resilient material are employed, such underlying cushions may be entirely dispensed with.

From the above description it will be apparent that there is thus provided a device 50 of the character described possessing the particular features of advantage before enumerated as desirable but which obviously is susceptible of modification in its form, proportion, detail construction or arrangement of parts, without departing from the principle involved or sacrificing any of its advantages.

While in order to comply with the statutes, the invention has been described in 60 language more or less specific as to certain structural features, it is to be understood that the invention is not limited to any specific details, but that the means and construction herein described comprise but one mode 65 of putting the invention into effect, and the

invention is therefore claimed broadly in any of its possible forms or modifications within the scope of the appended claims.

Having thus described my invention, I claim:—

70 1. In a railway tie construction of the character described, an elongated sleeper member adapted to receive one of the track rails, two separated spaced sleeper members to receive the other track rail, and intermediate means connecting the separate spaced sleeper members with the elongated sleeper member.

75 2. In a railway tie, a bifurcated skeleton construction, a sleeper block carried at the extremity of each arm of said bifurcated construction, and a sleeper block connecting the arms of said bifurcated construction.

80 3. In a railway tie construction, spaced receptacles or boxes adapted to be embedded in concrete in spaced relation one with the other, removable sleeper blocks positioned within the receptacles or boxes, and intermediate ties between the boxes embedded in the concrete body, substantially as specified.

85 4. In a railway tie construction, boxes or receptacles adapted to serve as forms for the molding of recesses or pockets in a concrete body, sleeper blocks positioned within the receptacles or boxes, means for supporting the sleeper blocks and receptacles on the track rails in spaced relation, and a body of concrete or similar material cast around said boxes or receptacles while supported upon the track rails, substantially as 90 specified.

95 5. In a railway tie construction, two spaced receptacles or boxes, a sleeper block located in each receptacle, transverse tie members connecting the receptacles or boxes at the extreme sides thereof, and additional tie members connecting said receptacles or boxes intermediate the first mentioned tie members.

100 6. In a railway tie, a receptacle or box, a sleeper block positioned therein, and a transverse tie member having a bight or recess therein in which the receptacle or box is interengaged.

105 7. The herein described method of railway track construction comprising suspending upon the track rails a skeleton tie comprising spaced receptacles or boxes connected one to the other by intermediate bonds or ties, and having a sleeper block positioned in each receptacle or box, and casting a body of initially plastic, and subsequently hardened material about the skeleton tie.

110 8. The herein described method of railway track construction comprising, providing an excavation to form the exterior confines of a concrete form, suspending interconnected sleeper blocks upon track rails traversing said excavation, and filling the excavation with concrete or like material in 115 120 125 130

which the sleeper blocks and intermediate connections will be embedded.

9. The herein described method of railway track construction comprising interconnecting the rails in predetermined spaced relation by suspending cross ties upon the railway rails, alining the rails to predetermined grade, and while said rails are supported at grade, pouring concrete or like material

around the rail connecting cross ties where- 10
by said cross ties will be permanently embed-
ded therein.

In testimony whereof, I have hereunto set
my hand this 7th day of June A. D. 1917.

RALPH J. WELLS.
